UNITED STATES PATENT OFFICE.

FRANZ KETTMANN, OF SALEM, OHIO.

CIGARETTE-MACHINE.

1,008,159.

Specification of Letters Patent.

Patented Nov. 7, 1911.

Application filed May 29, 1911. Serial No. 630,253.

To all whom it may concern:

Be it known that I, FRANZ KETTMANN, a subject of the Emperor of Germany, residing at Salem, in the county of Columbiana 5 and State of Ohio, have invented certain new and useful Improvements in Cigarette-Machines, of which the following is a specification.

This invention is a pocket implement for 10 the manufacture of cigarettes, and it has for its object to provide a device of this kind by the use of which a cigarette can be quickly and easily made, and also to provide a device which is simple in construction so 15 that it can be easily and cheaply manufactured.

With these objects in view, the invention consists in a novel construction and arrangement of parts to be hereinafter described 20 and claimed, reference being had to the accompanying drawing forming a part of this specification, in which drawing—

Figure 1 is an elevation of the device. Fig. 2 is a perspective view showing the 25 device open and ready for use. Figs. 3 and 4 are sections on the lines 3—3 and 4—4, respectively, of Fig. 1.

Referring specifically to the drawing, 5 denotes a cylindrical tube which is open at 30 one end and closed at its other end. In the tube is slidably mounted, so that it may be projected therefrom, a holder for the tobacco and paper of which the cigarette is made. This holder comprises a cylindrical 35 tube consisting of two longitudinal sections 6 and 7, respectively, connected by a hinge joint 8, so that said sections may be swung open and thereby facilitate the insertion of the tobacco. The tube 5 also contains a sta- 40 tionary plunger for pushing the tobacco from the holder into the paper tube, as will be presently described. The plunger comprises a stem 9 having, adjacent to the open end of the tube 5, a head 10, and the other 45 end of the stem is secured by a screw 11 in an aperture 12 made in the closed end of the tube. The plunger stem extends lengthwise through the tube 5 and is spaced there- 50 from a sufficient distance to accommodate the holder.

The section 6 of the holder has a short tubular extension 13 at its inner end containing a stop 13^a which engages the plunger

head at the end of the outward movement of the holder. The plunger head has an external longitudinal groove 14 to accommodate the knuckles of the hinge joint 8. The extension 13 and stop 13^a are provided with a threaded aperture to receive a screw 15 which passes through a longitudinal slot 16 in the tube 5, said screw being provided to afford convenient means for operating the holder.

In operation, the holder is slid out of the tube 5 and opened to receive the tobacco, 65 after which it is closed. By providing the holder with two hinged sections the tobacco can be readily inserted, and it can also be packed as tightly as desired. The tobacco having been placed in the holder, and the 70 latter closed, the paper is wrapped around the outside of the holder to form a tube, one end of the paper being moistened as usual to hold the paper in tubular form when it is slipped off the holder. The holder 75 is now drawn back into the tube 5, whereupon the paper tube is stripped off. The tobacco is pushed gradually out of the holder into the paper tube by the plunger head as the holder is retracted, and when the holder 80 is entirely withdrawn the cigarette is released in complete form from the holder. The holder and the part 13 thereof entirely close up the space between the plunger head and the tube 5 and thus prevent the paper 85 from being drawn into the latter when the holder is retracted.

I claim:

1. A cigarette making device comprising a tube open at one of its ends and closed at 90 its other end, a stationary plunger in the tube adjacent to the open end thereof, said plunger having a stem extending lengthwise through the tube and secured to the closed end thereof, and a tobacco and paper holder 95 comprising a tubular member which is slide- able into and out of the tube, the plunger being located inside the holder and the tube and holder being of substantially the same length to permit the entire holder to be re- 100 tracted into the tube.

2. A cigarette making device comprising a longitudinally slotted tube open at one of its ends, a stationary plunger in the tube adjacent to the open end thereof, a tobacco 105 and paper holder comprising a tubular mem-

ber slideable into and out of the tube, the plunger being located in the holder, and said holder consisting of longitudinal sections hinged together, one of the sections 5 having a tubular extension at its inner end, and a pin carried by said extension and projecting through the slot of the tube, the tube and holder being of substantially the same

length to permit the entire holder to be retracted into the tube.

In testimony whereof I affix my signature in presence of two witnesses.

FRANZ KETTMANN.
